SODIUM REFINING OF PETROLEUM OILS

Byron M. Vanderbilt, Westfield, N. J., assignor to
 Standard Oil Development Company, a corpora-
 tion of Delaware

No Drawing. Application May 1, 1950,
 Serial No. 159,380

8 Claims. (Cl. 196—23)

1

This invention relates to a process for refining mineral oils. The process is particularly directed to removal of gum forming substances, to the desulfurization or sweetening of oils, and to the color improvement of oils. The process consists of a treatment of the oil to be refined with a treating agent consisting of finely divided metallic sodium and an activator which may be an ether, a ketone, or an alcohol.

U. S. application 107,383, filed July 28, 1949, 10 by Byron M. Vanderbilt and Anthony H. Gleason, discloses a sodium refining process for mineral oils employing a secondary or tertiary alcohol as an activating agent for the sodium. This invention is related to the subject matter disclosed in the identified application and particularly discloses activators other than alcohols to be used in a process of this general character.

At the present time a great many refining processes are known for improving the quality of 20 mineral oils. These processes are generally directed to improving one or more characteristics of the oil so as to produce superior oils. For example, in the refining of gasolines, it is frequently desirable, or necessary, to improve the 25 odor of the gasoline by "sweetening" the gasoline so as to remove malodorous mercaptans, or so as to convert them to compounds which do not have an objectionable odor. Again refining processes are used to increase the resistance of the oil to 30 oxidation, decreasing the tendency of the oil to form objectionable gum deposits in storage and transit. The process of this invention is, therefore, directed to this general field, in which petroleum oils are refined in a manner to improve 35 the characteristics of these oils.

The process of this invention is of general application to petroleum oils, being suitable for the refinement of gasolines, heating oils, diesel fuels and so on. However, it is presently contemplated that the process is of principal importance as applied to the refining of gasolines and particularly of thermally or catalytically cracked gasolines. As applied in this manner the process of this invention provides a simple one step refining process capable of providing a stable and sweet gasoline having good engine cleanliness characteristics. This process is particularly advantageous since no caustic treatment or redistillation of the gasoline or petroleum fraction treated is required after the sodium-activator refining treatment.

Most broadly, the present invention may employ either sodium, potassium, or lithium in combination with a suitable activator. Thus, experiments have indicated that any one of these three metals may be employed, but however, for economic reasons, the use of sodium is to be preferred. Furthermore, the greater activity of potassium creates additional hazards in the handling of this metal. However, while this inven-

tion will be described with particular reference to the use of sodium, it is to be understood that other alkali metals may be employed.

It is essential in the conduct of the process to be disclosed that the sodium employed be in a finely divided form. Thus, as will be brought out, it is necessary that the sodium be in the form of fine particles having a particle size less than about 50 microns in diameter. Improved results are obtainable when the particle size is even smaller than this, as for example, less than about 30 microns and even in the range of about 2 to 10 microns. Suitable methods for obtaining sodium in such fine particles are known to the art. For example, sodium may readily be dispersed in a suitable vehicle such as a hydrocarbon oil by heating a mixture of sodium and the vehicle to a temperature above the melting point of the sodium and then thoroughly agitating this mixture. High speed agitators, homogenizers, colloid mills, or similar types of shear action dispersers are preferably employed to disperse the molten sodium in the form of very fine particles through the vehicle. The vehicle to be used may consist of virtually any hydrocarbon oil but is preferably a high boiling gasoline fraction substantially free of olefinic materials. A vehicle which has been found to be entirely suitable is a petroleum fraction boiling in the range of about 300 to 400° F. and consisting of a virgin naphtha. In order to maintain the sodium in the form of a stable dispersion of fine particles in such a vehicle, it is preferred that a dispersing or stabilizing agent be employed. Again, agents of this nature are known to the art and may consist for example of a resinous polymer or materials of a soap like nature such as sodium oleate, for example.

It has been found that several different types 40 of activators may be used in conjunction with the finely divided sodium to secure the desired refining results. Thus, as disclosed in U. S. application 107,383 formerly referred to, it had been found that secondary and tertiary alcohols are 45 suitable activators. It has now been found that ketones and ethers are also suitable as activators and in some cases are to be preferred to the use of alcohols. Of the ketones, acetone is outstanding and is materially better than methyl ethyl 50 ketone, methyl isopropyl ketone and methyl isobutyl ketone. Of the ethers, isopropyl ether has been found to be the best although other ethers such as ethyl ether, normal propyl ether, isobutyl ether, secondary butyl ether, benzyl ether, and various mixed ethers may be employed. As a 55 class the aliphatic ethers having four to ten carbon atoms are preferred.

In conducting the process of this invention it is generally preferred to prepare the dispersion 60 of sodium in a suitable vehicle and then to add

this dispersion of sodium together with the activator to the oil to be refined. The actual treating process of the oil with the dispersion of sodium and the activator is simply conducted by agitating the mixture in the liquid phase at a suitable temperature. The temperature to be employed is most broadly a temperature above about 150° C. although it is necessary that a more critical selection of temperature be made in the case of particular activators. For example, when employing secondary or tertiary alcohol, it is suitable to use temperatures above about 150° C. although preferably above about 200° C. and below about 250° C. In the case of ketones, the temperature may be in the range of 200° to 225° C. and the temperature of about 225° C. is preferred. Ethers are ineffective below about 150° C. and are particularly suitable for use at about 200° C. or higher. It has been found that materially improved results may be secured by employing critical temperatures for a given refining effect. Thus, in the case of sulfur removal, optimum results are obtained by refining at a temperature in the critical range of about 200° to 225° C.

Although there is a minimum temperature at which sodium and a given activator is effective, there is also a maximum temperature above which inferior results are obtained. This is well illustrated from a series of thermal naphtha treating runs which were carried out using one per cent of sodium, 6 microns average particle size, and 10 mole per cent of isopropanol as activator. The data are presented in the following table:

Temperature:	Time	Percent Sulfur	DFDF ¹	ASTM Break-down	Copper Dish Gum
Hours					
Control, no treat.		0.146	55.6	160	260
90° C.	1	0.127	39.6	365	10
200° C.	1	0.01	12.0	480	1.3
225° C.	1/2	0.02	11.3	415	4.7
250° C.	1/2	0.015	10.7	605	9.7
275° C.	1/2	0.03	13.6	265	15.2
300° C.	1/4	0.006	21.4	90	99 ²

¹ Diazonium fluoroborate deposit factor.

It may be observed that as the temperature is increased to about 200° the removal of sulfur becomes much more effective, accompanied with generally better refining results than at 90° C. In going to higher temperatures than 200° C., the copper dish gum values increase. In going to temperatures of the order of 275-300° C., properties other than sulfur content, seriously deteriorate. Based on these and other data it would appear that the optimum temperature range in order to get best overall improvement is in the range of 200-250° C. Similar data for sulfur removal from catalytic naphtha are given below when treated with 1% of sodium (2-6 microns diameter) and 10 mole per cent of isopropanol as activator:

Temperature	Contact Time	Percent Sulfur
Hours		
Control, no treat.		0.39
90° C.	1	0.27
120° C.	1	0.11
160° C.	1	0.10
225° C.	1/2	0.07
250° C.	1/2	0.08
375° C.	1/4	0.08
300° C.	1/4	0.10

As indicated, therefore, the refining process of this invention consists of agitating a mineral oil to be refined with a fine dispersion of sodium in the presence of an activator such as, acetone or isopropyl ether. The concentration of sodium to be employed is in the range of about 0.25% to 2.0% and is preferably about 0.5 to 1.0% by weight based on the mineral oil to be treated. As indicated the sodium is preferably added in the form of a dispersion in a suitable vehicle and the content of the sodium in this vehicle may be up to about 50% by weight or somewhat greater. The quantity of activator to be employed may be about 5 to 30 molar per cent but is preferably 5 to 10 mol per cent, based on the amount of sodium used. The minimum amount of activator is determined largely by the quantity necessary to stabilize the sludge formed in a finely dispersed condition:

20 The refining process does not appear to be greatly influenced by pressure although it is essential that sufficient pressure be employed to maintain the reaction system in the liquid phase. The time required to secure a suitable refining 25 effect is about 1/2 hour, although somewhat shorter or longer periods may be employed depending upon the temperature maintained.

After agitation under the indicated conditions, the mineral oil can readily be separated from the refining agents employed and the residues of these agents by a simple filtration process carried out below about 50° C. The effect of such a filtration is to remove sludge formed during the treating process together with other deleterious 35 products formed during the treatment. It has been determined that while filtration suitably purifies the treated mineral oil when conducted below about 50° C., filtration above 70° C. is not effective. While filtration at higher temperature 40 is effective to remove any sodium present, such filtration is not effective in removing other undesired constituents with the result that the refined oil product shows little improvement over the oil before treatment. It is to be understood, therefore, that filtration of the reaction mixture after the refining process has been carried out must be conducted at temperatures below about 50° C. When carried out in this manner no further treatment of the refined oil is required. For 50 example, it is not necessary to wash or distill this oil. However, in the case of higher boiling oils such as heating oils, which may contain acid materials such as naphthenic acids and certain phenols, it may be necessary to follow the filtration with a water or acid wash to remove oil soluble sodium salts.

In order to fully evaluate the process of this invention a series of experiments were conducted in which the different process variables were explored. In these tests a variety of inspections were employed to determine the improvement secured by the particular treatments. One test employed was an oxidation stability test which is identified herein as the ASTM Break-Down Test. This test is specifically ASTM Test D525-46. A third test which was carried out is known as the Copper-Dish-Gum Test and indicates the gum content of the petroleum oil in mg./100 cc. as obtained by heating the petroleum oil at 212° F. in a copper dish. Still another test employed was the Doctor Test which utilizes plumbite and a trace of free sulfur to indicate the presence or absence of mercaptans. Results of this test are indicated as "pass" or "did not pass" 60 corresponding to the absence or presence re-

spectively of mercaptans. Finally the last test employed to evaluate results was a test giving what is known as the "diazonium fluoborate deposit factor." This test indicates the engine cleanliness characteristics of gasoline. The test utilizes the coupling reaction which takes place between diazotised p-nitro aniline and certain unsaturated compounds (which cause engine fouling) to form a colored compound. Intensity of color formed after a given time interval is taken as an index of the deposit forming compounds present. In running the test the fraction of the sample boiling over 275° F. and purified by treatment with dilute acid and alkali and steam distillation to 3% bottoms is used. A 15 known quantity of this fraction is added to a solution of p-nitro-aniline diazonium fluoborate ($\text{NO}_2\text{C}_6\text{H}_4\text{N}=\text{NBF}_4$) in acetone and the optical density measured at intervals in a Hellige-Diller emission photometer. The optical density is 20 plotted against time and the value after 20 minutes read from the curve. The optical density multiplied by the ratio of the fraction boiling over 275° F. to the whole sample gives the diazonium deposit factor.

Results obtained by these tests are indicated hereinafter making reference to the inspections identified above.

EXAMPLE 1

Four hundred grams of thermal naphtha obtained by thermal cracking of reduced crude was mixed with four grams of finely dispersed metallic sodium in 4.5 grams of virgin naphtha boiling in the range 320-380° F. The mixture was then heated at 90° C. for one hour, cooled to 40° C., and the sludge and unreacted sodium removed by filtration. The filtrate was inhibited with the conventional inhibitor, N,N'-diisobutylparaphenylene diamine, in concentration of one pound per 5000 gallons and was then submitted to the evaluation tests indicated in Table 1.

EXAMPLE 2

This run was as in Example 1, except that 1.82 cc. of isopropyl ether was employed and the mixture heated at a temperature of 225° C. for one-half hour in a pressure bomb.

EXAMPLE 3

Example 2 was repeated except that the isopropyl ether was omitted.

Evaluation data from these three runs include the following:

Table 1

Run	ASTM Break-down	Copper Dish Gum	Percent Sulfur	Deposit Factor ¹
Control.....	160	12.9	0.146	55.6
Example 1.....	165	62	0.142	50
Example 2.....	490	2	0.015	10
Example 3.....	240	16	0.112	33

¹ Diazonium fluoborate deposit factor.

Referring to the table indicating the results of Examples 1, 2 and 3, it will be observed that the use of isopropyl ether at a temperature above 225° C. was very advantageous. Thus, comparing Example 2 to Example 1, it will be noted that the presence of the ether at the higher refining temperature was responsible for material improvement in each of the inspections. This result was not due to the difference in refining

temperature as shown by Example 3 since finely dispersed sodium alone without the isopropyl ether as shown by Example 3 even at the temperature of 225° C. does not provide an equivalent refining effect. It may be noted that as yet the mechanism of the activation effect contributed by the ether is not understood, although experiments have indicated that at about 200° C. there is a slow reaction between the ether and sodium to form a white substance. The comparison of Examples 1 and 3 to the control inspections is particularly significant as showing the ineffectiveness of sodium alone, without an activator, to effect any substantial improvements.

EXAMPLE 4

As still another comparison of the use of sodium alone and sodium with an activator in the refining of an oil, a thermal naphtha distilling in the range of 225 to 400° F. was employed. In the case in which finely divided sodium alone was employed at 90° C. in a weight per cent of 0.75%, the sodium provided little or no refining effect. Similarly, when 10 mol per cent of isopropyl ether based on the sodium was employed, no appreciable refining effect took place. This example again indicates that the ether does not act as an activator at temperatures of, or below 90° C.

EXAMPLE 5

A thermal naphtha boiling in the range 225° to 400° F. was employed having an initial sulfur content of 0.146% and having a deposit factor of 55. When this naphtha was treated with 1% of sodium having a particle size of 2 to 6 microns and 7.5 mol per cent of ethyl ether, it was found that the sulfur content had been cut down to 0.016% and the deposit factor had dropped to 14.5. This experiment therefore indicates that ethyl ether, as well as isopropyl ether is a suitable activator in sodium refining.

EXAMPLE 6

In a similar run again employing a thermal naphtha having the inspections given in the former example and employing 1% of sodium activated with 10 mol percent of acetone, it was found that the sulfur content was reduced to .017% and the deposit factor was reduced to 13. It is apparent from these data that acetone serves as an activator in sodium refining.

EXAMPLE 7

Experiments were also conducted employing a heavy catalytic naphtha having a boiling range of 330 to 438° F. In each experiment 400 parts of this naphtha were agitated with 4 parts of sodium consisting of a 50% dispersion in a virgin naphtha boiling in the range of about 320° to 380° F. This sodium dispersion also contained a low molecular weight polymer and sodium oleate as dispersing agents. The sodium had a particle size in the range of 2 to 6 microns. Isopropyl alcohol, tertiary butyl alcohol, isopropyl ether and acetone were then added to the mixture of naphtha and sodium in the mol proportions indicated in the following table. The reactants were sealed in a pressure-bomb and heated with shaking for one-half hour at 250° C. Thereafter the contents of the bomb were cooled below 50° C. and the sludge was removed by filtration. The

results of these tests are indicated in the following table:

Activator	Mole Percent	Percent Sulfur	DFDF ¹
No treat		0.385	13.0
Isopropyl alcohol	10	0.078	3.1
T-Butyl alcohol	10	0.103	3.5
Isopropyl Ether	7.5	0.123	5.0
Acetone	10	0.108	5.9

¹ Diazonium fluoborate deposit factor.

It is apparent from these data that each of the activators tested is effective to provide substantial refining effects as indicated by the sulfur reduction and the improvement in the diazonium fluoborate deposit factor.

EXAMPLE 8

The use of ethers is particularly advantageous since their concentration is not critical and they may remain in the gasoline as valuable fuel components. The following data illustrate that the concentration of isopropyl ether is not critical. These data are from runs using thermal naphtha with 1% of sodium at 225° C. for one hour. The sodium was as a dispersion of 2-6 microns in a virgin naphtha of 320-380° F. boiling range.

Activator	Percent Activator ¹	Final Sulfur	DFDF ²
No treat		0.146	55
Isopropyl Ether	7.5	0.015	10
Do	15	0.011	23
Do	30	0.016	19
Ethyl Ether	7.5	0.016	14.5

¹ Mole percent.

² Diazonium fluoborate deposit factor.

One run with ethyl ether is also shown for comparative purposes. It may be noted that although use of 7.5 mol per cent of isopropyl ether is optimum of the three concentrations tested, excellent reduction in sulfur content was obtained with as high as 30 mol per cent of the ether.

Having now fully described the invention what is claimed is:

1. The process of improving the oxidation stability of petroleum oils in which the oil to be treated is maintained at a temperature above about 150° C. and is contacted in liquid phase with about 0.25 to 2.0% of finely divided sodium and about 5 to 30 mol per cent of an activator based on the quantity of sodium, said activator being a compound selected from the group consisting of ethers and ketones.

65

2. The process defined by claim 1 in which the said finely divided sodium consists of particles of sodium smaller than about 50 microns in diameter.

3. The process defined by claim 1 in which the said petroleum oil is a cracked gasoline fraction.

4. The process of improving the oxidation stability and engine cleanliness of a cracked gasoline consisting of agitating the said gasoline in liquid phase in contact with about 0.25 to 2.0 per cent of sodium having particles less than about 50 microns in diameter and about 5 to 30 mol per cent based on the sodium of isopropyl ether, said agitation being carried out at a temperature above 150° C. and below about 250° C. and thereafter cooling said mixture and filtering below about 50° C. whereby a refined gasoline is obtained.

5. The process defined by claim 4 in which the said cracked gasoline consists of a thermally cracked gasoline fraction.

6. The process defined by claim 4 in which the said gasoline consists of a catalytically cracked gasoline fraction.

7. The process according to claim 4 in which the said temperature at which agitation is conducted is in the range of 200 to 225° C.

8. The process of improving the oxidation stability of a petroleum oil in which the said oil is contacted in liquid phase with finely divided sodium and an aliphatic ether having from 4 to 10 carbon atoms, said contact being carried out at temperatures above 150° C. the sodium being present in proportions of about 5 to 1% based on weight of oil being treated and said ether being employed in proportions of about 5 to 10 molal per cent based on the quantity of sodium employed.
